(57) **CLAIM**

The ornamental design for a casing for portable electronic device, as shown and described.

DESCRIPTION

FIG. 1 is a front perspective view of a casing for portable electronic device showing my new design.

FIG. 2 is a rear perspective view thereof.

FIG. 3 is a front view thereof.

FIG. 4 is a rear view thereof.

FIG. 5 is a left end view thereof.

FIG. 6 is a right end view thereof.

FIG. 7 is a top view thereof.

FIG. 8 is a bottom view thereof.

FIG. 9 is a front perspective view thereof, showing an in-use position; and,

FIG. 10 is a rear perspective view thereof, showing an in-use position.
